UNITED STATES PATENT OFFICE.

HEBER E. MARTING, OF RUTHERFORD, NEW JERSEY, ASSIGNOR TO WESTERN ELECTRIC COMPANY, INCORPORATED, OF NEW YORK, N. Y., A CORPORATION OF NEW YORK.

NUT AND BOLT LOCKING DEVICE.

Application filed December 6, 1923. Serial No. 678,931.

To all whom it may concern:

Be it known that I, HEBER E. MARTING, a citizen of the United States of America, residing at Rutherford, in the county of Bergen, State of New Jersey, have invented 5 certain new and useful Improvements in Nut and Bolt Locking Devices, of which the following is a full, clear, concise, and exact description.

10 This invention relates to nut and bolt holding devices and more particularly to locking devices which are designed to fasten bolts securely in place when used in connection with concrete inserts and the like.

15 It is the object of this invention to provide an anchoring device for a bolt or nut whereby shaft hangers, brackets, pedestals or other devices may be readily and securely attached to their supports. These supports, 20 so called concrete inserts, consist of a socket member having an opening or groove in its under-side to receive the bolt head. When the insert is embedded in the concrete its underside is flush with the concrete surface. 25 The bolt may then be positioned at any point along the groove.

A common method of supporting structures is by the use of square head bolts which are introduced in the concrete insert 30 at specially enlarged openings placed at convenient intervals along the groove.

35 A disadvantage of this method is apparent when it is realized that it is some times necessary to insert one structure alongside another particular structure. If there is no enlarged opening near the desired position all existing structures between the nearest opening and the desired position must be removed, the structure inserted and the 40 existing structures replaced. This involves a great loss of time and labor. By eliminating the enlarged openings and providing a T head bolt which may be inserted at any point along the slot, this difficulty is obviated.

45 It is a feature of this invention to provide flexible means for anchoring bolts in concrete ceilings, walls and floors.

Another feature of this invention is the 50 provision of a specially constructed locking device for guarding against undesired turning of a bolt in the slot of its associated support.

Referring now specifically to the drawings:

Fig. 1 is a section through a concrete insert showing a bolt to which is attached a structure to be supported. The head of the bolt has been inserted in the groove or slot and the locking device securely fastened in 60 position for preventing the bolt from turning.

Fig. 2 is another view of the concrete insert taken at right angles to that shown in Fig. 1 and illustrates the way in which 65 the locking device grips the bolt head.

Fig. 3 is a perspective elevation of the locking device, and

Fig. 4 shows the relation of the bolt and the locking device before being introduced 70 into the groove.

Referring specifically to Figs. 3 and 4, it will be seen that the locking device consists of a rigid member having a base 1 in which is an aperture 2 through which shank 3 75 of the bolt may be passed. Integral with the base 1 and symmetrically positioned with respect to the aperture 2, are two upwardly projecting rigid members 4 and 5. The length-wise dimensions of these members 80 is slightly less than the width of the aperture or slot of the concrete insert 7 hereinafter described. The distance between the upper edges of these members is such as just to admit the insertion of a T-head bolt 85 as shown in Fig. 2. The aperture 2 is preferably circular in section but may be of any other convenient shape desired.

In Figs. 1 and 2 the bolt and locking device are shown in the proper position for supporting structure 9 or the like. An insert 7 of well known design is embedded in a concrete ceiling, wall or floor 8 so that the shoulders 15 of its slot are flush with the ceiling, wall or floor surface. The locking device shown in Fig. 3 is then slipped over a threaded T-head bolt so that the shank 3 projects through aperture 2. The locking device is loosely secured upon the bolt by means of nut 10, as shown in Fig. 4. 100 Bolt head 6 is then inserted lengthwise into the slot of insert 7 and given a quarter turn.

With the bolt in this position the locking device is slid along the shank of the bolt until the base 1 is flush with the under surface of insert 7 and projecting members

4 and 5 engage with the sides of bolt head 6, as shown in Figs. 1 and 2. The whole is then securely fastened by means of nut 10 and the structure 9 to be supported is then secured to shank 3 in an obvious manner by means of flanges 13 and 14 and nuts 11 and 12.

It is clearly evident from an inspection of Figs. 1 and 2 that bolt head 6 cannot 10 turn since it is gripped between projecting members 4 and 5 which themselves cannot move due to the fact that they fit snugly into the slot as above mentioned.

While this locking device has been 15 closed in conjunction with a concrete insert, it is obvious that it may be employed generally for locking bolt heads.

What is claimed is:

1. The combination with an insert for 20 concrete construction comprising a hollow body portion with internal supporting flanges forming an elongated entrance slot therebetween of a T-headed bolt, the head of which when inserted through said slot 25 and rotated is supported by said flanges, an apertured locking plate having projections integrally formed therewith for engaging the head of said bolt and the faces of said slot, and means to clamp said bolt, plate 30 and insert together, thereby preventing the rotation of said bolt.

2. The combination, with a supporting member having a slot therein, of a T-headed bolt, the head of which when inserted

through said slot and rotated is not withdrawable therethrough, and an apertured locking plate having projections integrally formed therewith for engaging the head of said bolt and the faces of said slot for locking said bolt against rotation. 35 40

3. The combination with a supporting member having a slot therein, of a T-headed bolt, the head of which when inserted through said slot and rotated is not withdrawable therethrough, and an apertured locking plate having oppositely disposed 45 projections of substantially the width of said slot, said plates when placed within its projections extending through said slot and with the outer edges of said projections embracing the side faces of the head of said bolt, locking itself and said bolt from turning. 50

4. The combination with an insert for concrete construction comprising a chambered body portion with internal supporting flanges forming an elongated entrance slot, an attaching member adapted for insertion within said body portion at any point along said slot, and a locking device 55 assembled with said member for engagement with the faces of said slot and with said attaching member to retain said member within said body portion. 60

In witness whereof, I hereunto subscribe 65 my name this 30th day of November A. D., 1923.

HEBER E. MARTING.
